(57) **CLAIM**

The ornamental design for a handheld corn sheller as shown and described.

DESCRIPTION

FIG. 1 is an exploded top perspective view of a handheld corn sheller showing the claimed design;

FIG. 2 is an exploded bottom perspective view thereof;

FIG. 3 is an exploded front elevational view thereof;

FIG. 4 is an exploded rear elevational view thereof;

FIG. 5 is an exploded left side view thereof;

FIG. 6 is an exploded right side view thereof;

FIG. 7 is top plan view of the handheld corn sheller shown in an assembled configuration;

FIG. 8 is a bottom plan view thereof;

FIG. 9 is a cross-sectional view of the handheld corn sheller taken along line 9-9 shown in FIG. 3; and,

FIG. 10 is a top perspective view of the lower portion of the handheld corn sheller shown on its own for clarity of the disclosure.

The broken lines show portions of the handheld corn sheller that form no part of the claimed design.
